UNITED STATES PATENT OFFICE.

BARNET RUBENSTEIN, OF CHICAGO, ILLINOIS.

MINER'S PICK.

SPECIFICATION forming part of Letters Patent No. 608,716, dated August 9, 1898.

Application filed October 2, 1897. Serial No. 653,870. (No model.)

To all whom it may concern:

Be it known that I, BARNET RUBENSTEIN, a citizen of the United States of America, residing at Chicago, in the county of Cook and State of Illinois, have invented certain new and useful Improvements in Miners' Picks, of which the following is a specification.

My invention relates to certain improvements in miners' picks, designed for the purpose of making said picks less burdensome to carry and also to avoid the necessity of frequently sharpening the same.

To such end the invention consists in certain novel features clearly illustrated and described below.

The drawings show, in Figure 1, a side elevation of the complete pick; in Fig. 2, a horizontal section in line 2 2 of Fig. 1; in Fig. 3, an end view of the head of the pick with certain parts broken away to show the construction thereof, and in Figs. 4 and 5 modified forms of points.

The handle A of the pick is preferably made in three sections consisting each of a wooden outside portion a a' a'' and an inner metal rod a^3 a^4 a^5 . The wooden pieces are preferably joined together to prevent rotation of one with respect to the other and strengthened at the joints by means of ferrules B B'.

The sections of the rod are preferably adapted to be screwed together, the section a^5 being provided with a button a^6 , fitted to the hole in the head of the pick and having a flange a^7 , extending over the adjacent surface of said head, and the section a^3 being preferably screw-threaded at the end and provided with a wing-nut a^8 . This handle may be readily taken apart and carried in short sections, and when it is desired to use it the sections of the rod may be secured together, inserted in the wooden portions, and the whole handle tightened up by means of the wing-nut a^8 , which at the same time forces the head down upon the handle by reason of the flange a^7 upon the button a^6 .

The head D of the pick is provided with the usual hole for the insertion of a handle, but is also formed in sections d d' d'' , the middle or main portion d being short enough to be conveniently carried along with the sections of the handle and the end pieces d' d'' , form-

ing the points, being joined to the middle portion by means of tenons d^3 d^4 , fitted to mortises d^5 d^6 in the portion d . They are locked against displacement by means of pins d^7 d^8 , 55 driven into holes in the respective portions of the head. This construction of the head has a double advantage. It not only divides the same up into sections short enough to be conveniently carried, but it also dispenses with 60 frequent sharpening of the points, inasmuch as a number of these points can be carried and a dull point replaced in a few minutes with a new one. It also enables a great variety of points to be carried, which would be 65 impossible were it necessary to carry separate picks for each pair of said points. Figs. 4 and 5 illustrate two of the many points which might be of great use. Fig. 5 is a sort of spade-point, and Fig. 4 is a point which when turned 70 in the plane of the handle may be used as a hatchet and when turned at right angles thereto as an adz. It should be noticed that the joints in the handle do not coincide with those in the metal rod, so that the full lateral 75 strength and rigidity of the clamping-rod is obtained at the joints in the handle and the full lateral strength of the handle at the joints in the rod.

I claim as new and desire to secure by Letters Patent—

1. In a tool of the class described, a jointed handle having a clamping-rod extending through the same, said rod being composed of sections not coincident with those of the 85 handle; substantially as described.

2. In a tool of the class described, a handle composed of sections connected by joints adapted to prevent rotation of one section upon the other and a clamping-rod extending through the same and made up of the sections not coincident with those in the handle; substantially as described.

In witness whereof I have hereunto set my hand, at Chicago, in the county of Cook and State of Illinois, this 22d day of September, 95 A. D. 1897.

BARNET RUBENSTEIN.
